(57) **CLAIM**

The ornamental design for an apparatus for dispensing a cushioning wrap material, as shown and described.

DESCRIPTION

FIG. 1 is a perspective view of a first embodiment of an apparatus for dispensing a cushioning wrap material, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of an apparatus for dispensing a cushioning wrap material;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The portions of the apparatus for dispensing a cushioning wrap material shown in broken lines illustrate unclaimed portions of the article and form no part of the design. Shade lines in the drawings represent the character or contours of the claimed surfaces, and are not to be confused with surface indicia.
